UNITED STATES PATENT OFFICE.

CHARLES S. BIRD, OF WALPOLE, MASSACHUSETTS.

PROCESS OF PRODUCING PAPER.

Application filed February 9, 1925. Serial No. 8,062.

To all whom it may concern:

Be it known that I, CHARLES S. BIRD, a citizen of the United States, residing at Walpole, in the county of Norfolk and State 5 of Massachusetts, have invented certain new and useful Processes of Producing Paper, of which the following is a specification.

This invention pertains to an improved process of producing paper and more particularly to an improved process of subdividing a web of paper into a plurality of strips. The invention is especially applicable to the slitting of that class of paper ordinarily manufactured in webs having 10 certain zones or areas extending longitudinally of the web of a thickness less than the remainder of the body, the slitting being effected through or immediately adjacent to the thin portions thereby producing strips 15 or sheets having one or both edges thin.

The main object of the invention is to provide an improved process for slitting the paper so that the strips produced will be free from wrinkles and ragged or cut edges.

Heretofore paper of the kind above mentioned has been slit either prior to the drying operations as described in the patent to Hanscom, No. 702,205, dated June 10th, 1902, or in the usual manner, on most all 25 paper machines, after the calendering operation and prior to cutting the strips into sheets or to winding the same into rolls. For certain classes of uses of paper it has been found undesirable to utilize the process of slitting prior to the drying operation. In such cases it has been customary 30 to slit the web according to the usual paper-maker's practice; that is, after the paper has passed through the calender rolls, with 35 the result of causing unequal strains and stresses upon the thin portions of the web thereby causing wrinkles or calender cuts and consequently rendering a large portion 40 of the paper unfit for commercial use. The 45 present invention affords a method whereby such wrinkles and calender cuts in the edges of the sheet are practically if not wholly eliminated. What is more, the sheets produced by the present method will expand 50 but little when subjected to moisture.

With a view of more clearly outlining the process and illustrating means whereby the process may be carried out, reference will be had to the annexed drawings, wherein

Fig. 1 is a sectional elevation of a drier, a calender stand, an interposed web slitting

means and a spreader for the web after it has been slit;

Fig. 2 a plan view thereof with parts broken away;

Fig. 3 a transverse sectional view on an enlarged scale on the line III—III of Fig. 2, illustrating the spreader; and

Fig. 4 a detail view showing a slightly modified arrangement of the driers and slit- 65

In so far as the process is concerned, the drawings are to be considered as merely illustrative.

Referring to Figs. 1 to 3, the web designated by 1 emanating from the wet end of the machine (not shown) passes over and about the drier drums 2, 3 and 4, as is usual. Located adjacent drum 4 in suitable fixed bearings is a roller 5 over which the web 70 passes immediately it leaves said drum. Located to the rear of the roller is a fixed rail or bar 6 which forms the support for a series of brackets 7 adjustable longitudinally thereof with a view of securing the 75 spacing desired between the brackets. To each bracket there is pivotally secured a weighted lever 8, each lever in turn carrying a slitting roll or disk 9. The slitting disks bear upon the roller 5 and as a consequence slit the web 1 into a series of strips as the same is drawn beneath the disks. The lines of severance may be centrally of the thin longitudinally extending portions 80 of the web or at the edge thereof and such 85 results may be effected by the proper adjustment and spacing of the brackets along the bar 6. The web after having been cut into strips, or more properly speaking, the strips, passes over a spreader illustrated as 90 a flexible bar 10 secured to the upper ends of a series of brackets 11, which latter in turn are secured for vertical adjustment to a fixed bar 12.

The spreader bar 10 will be given such 100 upward curvature as will produce the desired spread or spacing between the various web strips as they pass to the upper portion of the stand of calendering rolls designated generally by 13.

In Fig. 4 a slight variation of the drying drums and slitters is shown. In this instance the slitters act upon the web at a point between the last two drums 3^a and 4^a, the web at such time having been sufficiently dried by the drums 2^a and 3^a to allow the slitters to act upon the thin portions of

the web without disrupting the same. The arrangement first described is, however, preferred.

From the foregoing it will be seen that the web is slit into strips immediately after or at the time of the drying operation, and prior to the calendering operation, and, as above noted, it has been demonstrated in actual practice that the product produced 10 possesses different properties which are better suited for some purposes than that which results from the old method of cutting, namely, slitting before drying the web. The paper is smoother and does not expand as 15 readily in the presence of moisture. This latter quality is due to the fact that the web is held under lateral tension by the drying drums (or some of them at least) prior to its being cut into strips. When cut before 20 being dried, the fibers contract to a greater extent than after drying, and consequently will expand to a greater extent in the presence of moisture.

Where sheets having a thinned edge or 25 two thinned edges are employed in the manufacture of articles which require accuracy of size, such, for instance, as high grade shot shells, the presence of cuts or wrinkles along such thinned edges is fatal to a su-

erior product. With my method of producing the strips from which the sheets may be cut, no difficulty arises as the edges are smooth and even, being free from wrinkles and calender cuts.

What is claimed is:

1. That process of producing strips of paper having thin edges from a web having thin zones extending longitudinally thereof, which consists in drying the web; slitting the same along the thin zones; and thereafter calendering the strips. 35 40

2. That process of producing strips of paper having thin edges from a web having thin zones extending longitudinally thereof which consists in passing the web through a drier; slitting the web along such zones as it leaves the drier; spreading the strips; and finally calendering the separated strips. 45

3. In a machine for producing strips of paper having at least one thin edge comprising in combination means for drying a web having at least one thin section; means for slitting the web at said drying means; means for spreading the strips thus produced; and means for calendering the strips. 50 55

In testimony whereof I have signed my name to this specification.

CHARLES S. BIRD.
